UNITED STATES PATENT OFFICE.

GEORGE N. LOOMIS, OF RUTH, NEVADA.

RAILWAY BRAKE MECHANISM.

Application filed August 11, 1925. Serial No. 49,571.

To all whom it may concern:

Be it known that I, GEORGE N. LOOMIS, a citizen of the United States, residing at Ruth, in the county of White Pine and State 5 of Nevada, have invented certain new and useful Improvements in Railway Brake Mechanisms, of which the following is a specification.

This invention relates to railway car 10 equipment and more particularly to a hand brake mechanism.

Briefly stated, an important aim of this invention is to provide simple means whereby the brakes of a railway car may be operated by hand from a remote point without the necessity of employing the conventional connecting chains which have been the cause of frequent accidents and loss of life in the past.

20 A further and equally important object of the invention is to provide a hand brake mechanism of the character specified having simple means whereby the same may be operatively connected to the air brake system in such a manner that the brake shoes may be applied by an operation of the air brake system without conflict with the operating members of the hand brake mechanism.

Another and important feature of the invention resides in the fact that the principal parts of the invention may be quickly and easily exposed for inspection and detached if desired without removing the main supporting frame and other parts.

35 A further and equally important object of the invention is to provide a hand brake mechanism which may be applied to rolling stock of various types, such as box cars, logging cars, and flat cars.

40 Another object is to provide a hand brake mechanism which may be easily applied to standard rolling stock without a material alteration thereof either during the course of manufacture or at any time thereafter.

45 Other objects and advantages will be apparent during the course of the following description.

In the accompanying drawings forming a part of this application and in which like 50 numerals are employed to designate like parts throughout the same,

Figure 1 is a side elevation of the improved hand brake mechanism applied;

Fig. 2 is a plan view of a motion transmitting mechanism embodied in the invention;

Fig. 3 is a vertical transverse sectional view taken on line 3—3 of Fig. 1;

Fig. 4 is a detail transverse sectional view taken on line 4—4 of Fig. 2;

Fig. 5 is a plan view illustrating the application of the invention to a flat car.

In the drawings, the numeral 5 designates a car having sill blocks 6 to which the side or angle members 7 of a rectangular frame are bolted or otherwise secured. The frame 60 is provided at one end with an upwardly extending flange 8 which may be secured by bolts or other fastening devices to one end of the car as clearly shown in Fig. 1.

In carrying out the invention the rectangular frame is preferably formed from a single piece of metal provided with longitudinal and transverse incisions which define partly severed portions which may be bent 70 downwardly to define spaced parallel guide members or flanges 10. These flanges 10 form a guiding means for a block 11 through which a screw 12 is threaded as clearly shown in Fig. 2. One end of the screw 12, which, incidentally, has a worm 80 thread, is rotatably extended through a bearing member 14 at one end of the rectangular frame. The other end of the screw 12 is rotatably extended through the eight portion of a U-shaped bracket 16 and is provided with a pinion 18 which is in constant mesh with a pinion 20 on a vertical shaft 21. Fig. 1 plainly illustrates that the lower portion of the vertical shaft 21 is rotatably extended through the upper and 85 lower members 22 and 23 of the bracket 16 and is held in place thereby. The upper portion of the shaft 21 is provided with the conventional hand wheel 25 designed to be turned by the brakeman.

When the hand wheel 25 is turned the screw 12 is turned for moving the block 11 longitudinally of the frame and when the block is thus moved a connecting link or yoke 28 extended through openings 29 in the block is also moved longitudinally to swing the lever 30 to an operative position whereby the shoes 31 and 32 are applied.

It is important to note that the sides of 100 the yoke 28 are slidable through side grooves in the block 11 so that the brake shoes 31 and 32 may be applied by the air brake system independently of the above described mechanism. More specifically, when the air 110

brake system is operated to apply the shoes 31 and 32 the lever 30 will, of course, be swung to an operative position and this will move the yoke 28 longitudinally with respect to the block 11. Fig. 2 plainly illustrates that nuts 34 are threaded on the sides of the yoke 28 and establish a driving connection between the block and the yoke when the screw 12 is turned in the proper direction. That is to say, when the block 11 is moved toward the pinion 18 by the turning of the screw 12 the yoke 28 will be moved in the same direction for the application of the brake shoes. Or the yoke 28 may be moved in the direction of the pinion 18 independently of the block 11 by the operation of the air brake system.

The yoke 28 and more particularly the side of the same, have a generous bearing area in the block 11 and also have sliding contact with the depending end wall 14 of the frame so that the yoke will not weigh on the lever 38.

A hand brake system constructed in accordance with this invention entirely eliminates the chain ordinarily employed as a connecting medium between the shaft 21 and the lever 30. This chain frequently breaks and results in loss of life and damage to the rolling stock. Also, the usual pawl and ratchet mechanism employed in the present day hand brakes is entirely eliminated.

The invention forming the subject matter of this application may also be carried out in connection with a flat or logging car as shown in Fig. 5 and by reference to this figure it will be seen that the bracket 16 may be easily changed from a vertical position to a horizontal one and securely bolted in place so as to dispose the operating shaft 60 horizontally. When the operating shaft 60 is thus positioned, the hand wheel 61 of the same is located at or near one side of the car and within convenient reach of the brakeman or other attendant.

The improved hand brake mechanism may be easily applied to standard rolling stock either during manufacture or at any time thereafter without an elaborate alteration of the rolling stock. The improved braking mechanism may be easily maintained since the same consists of comparatively few parts and all of these are highly accessible and are, therefore, easily lubricated and inspected from time to time. The frame 7 is securely bolted to a suitable part of the car and is securely held in place to withstand the strain to which the same is subjected and to hold all parts carried thereby in their proper positions.

Figs. 1, 3 and 4 plainly illustrate that the frame 7 is provided with a detachable bottom plate 60 held in place by bolts 61. The

bottom plate may be quickly removed for exposing the block 11, the screw 12 and the inner portion of the yoke 28 for inspecting these parts, lubricating the same, or possibly renewing them. When the bottom plate 60 is removed, the block 11 may be dropped through the under side of the frame subsequent to the removal of the screw 12. To remove the screw 12, it is first necessary to detach the cotter pin 65 at the lower portion of the shaft 21 and then detach the collars 24 and the pinion 20 whereupon the shaft 21 may be removed. Fig. 1 plainly shows that the pinion 20 is provided with a sleeve-like hub 66 which rests upon the lower collar 24 and thereby prevents binding of the pinion 20 with the pinion 18.

The shaft 21 having been removed, the pinion 18 may be detached from the screw 12 so that the screw may in turn be removed through the bottom of the frame. It is thus seen that all of the major parts of the invention may be quickly disassembled for the removal of any parts found worn or weakened as the result of long use. Fig. 3 illustrates that the sides of the yoke 28 may be spread somewhat so that the same may be removed from the openings 29 which extend out through the sides of the block 11.

Having thus described the invention, what is claimed is:

1. A railway brake equipment comprising a frame having means whereby the same may be attached to a railway car, said frame being provided with depending flanges defining guides, a block positioned between said guides, a screw connected to said block, a yoke having side members slidably connected to said block, said block being provided with openings extending out through the sides thereof for the reception of the sides of said yoke, and nuts threaded on said yoke at one side of said block.

2. A railway brake equipment comprising a frame having means whereby the same may be attached to a railway car, said frame being provided with guides, a block positioned between said guides, a screw connected to said block, a yoke having side members slidably connected to said block, said block being provided with openings extending out through the sides thereof for the reception of the sides of said yoke, nuts threaded on said yoke at one side of said block, a bracket secured to one end of said frame, an operating shaft rotatably extending through said bracket, pinions mounted on said shaft and said screw, said pinions being detachable whereby the shaft and the screw may be detached, and a protecting plate extending across the bottom of said frame and being detachably secured thereto.

3. A hand brake mechanism for railway cars comprising a frame having downwardly directed spaced parallel flanges constit-

- tuting guides, a block slideable between said guides and being provided with openings, a feed screw threaded through said block, a yoke having approximately parallel sides
 5 arranged between said guides and detachably positioned in said openings, nuts threaded on said sides and engaged with one side of said block, said yoke being provided with means whereby the same may be connected to a brake lever, a bracket of U-shaped formation secured to one end of said frame, an operating shaft extending through said bracket, pinions mounted on said shaft and said screw and being detachable, collars
 10 positioned between and engaging opposite sides of said shaft, said bracket being adjustable to a vertical or horizontal position.
 4. A hand brake mechanism for railway cars comprising a frame having guides, a block slideable between said guides and being provided with openings extending for the full length thereof and opening out through opposite sides, a feed screw threaded through said block, a yoke having approximately parallel sides arranged between said guides and detachably positioned in
 15 said openings, nuts threaded on said sides and engaged with one side of said block, said yoke being provided with means whereby the same may be connected to a brake lever, a bracket of U-shaped formation secured to one end of said frame, an operating shaft extending through said bracket, pinions mounted on said shaft and said screw and being detachable, collars positioned between and engaging opposite sides of said shaft, said bracket being adjustable to a vertical or horizontal position, and a protecting plate extending across the bottom of said frame and protecting said screw and said block, one end of said frame being provided with means guiding said yoke.
